US00D835115S

(12) **United States Design Patent** (10) Patent No.: **US D835,115 S**
Westergård et al. (45) Date of Patent: ** Dec. 4, 2018

(54) **SUPPORT FOR LAPTOP COMPUTERS**

(71) Applicant: **FREEDESK AB**, Lomma (SE)

(72) Inventors: **Stefan Westergård**, Bjärred (SE);
Martin Stark, Veberöd (SE); **John Stangdell**, Tyresö (SE); **Patrik Bruzelius**, Bjärred (SE)

(**) Term: **15 Years**

(21) Appl. No.: **35/503,607**

(22) Filed: **Aug. 2, 2017**

(80) **Hague Agreement Data**

Int. Filing Date: **Aug. 2, 2017**

Int. Reg. No.: **DM/097394**

Int. Reg. Date: **Aug. 2, 2017**

Int. Reg. Pub. Date: **Sep. 1, 2017**

(30) **Foreign Application Priority Data**

Feb. 6, 2017 (EM) 003741495-0003

(51) **LOC (11) Cl.** **08-07**

(52) **U.S. Cl.**

USPC **D14/447**

(58) **Field of Classification Search**

USPC D14/447, 439, 451, 452, 457

CPC A47B 21/04; A47B 2097/006; A47B 2097/005; A47B 2023/049
